UNITED STATES PATENT OFFICE.

OLIVER S. SLEEPER, OF BUFFALO, NEW YORK, ASSIGNOR TO BUFFALO FOUNDRY & MACHINE COMPANY, OF BUFFALO, NEW YORK, A CORPORATION OF NEW YORK.

Mounting for Fusion Kettles.

Application filed November 10, 1919. Serial No. 336,801.

To all whom it may concern:

Be it known that I, OLIVER S. SLEEPER, a citizen of the United States, residing in Buffalo, in the county of Erie and State of New York, have invented new and useful Improvements in Mountings for Fusion Kettles, of which the following is a specification.

This invention relates to means for mounting kettles in which materials, such as carbolic acid, beta-naphthal, resorcin, nigrosine, &c., are fused and mixed, and it has for its purpose the production of means whereby the mixing device may be easily and conveniently inserted and removed from the kettle and the latter may be readily and quickly tilted for discharging its contents without liability of spilling or slopping over any of the material.

20 In the accompanying drawings: Figure 1 is a top plan of my improved mounting for kettles and means for agitating its contents. Figure 2 is a vertical longitudinal section of the same.

25 Similar characters of reference relate to like parts in both views.

10 represents the heating furnace which may be of any suitable construction to heat the contents of the kettle or pot 14 which 30 is supported over the top of the furnace. 11 is a supporting frame mounted on the upper end of the furnace and provided on its front part with a spout 12 which receives the treated material from the kettle and 35 discharges the same into any suitable receptacle. Above this frame is arranged a saddle 13 of annular form which normally rests on the frame and is pivotally connected at its front part with the front part of 40 the frame so as to be capable of tilting forwardly relatively thereto by means of two horizontal pivot pins 15 each passing through corresponding eyes or lugs 16, 17 formed respectively on the frame and saddle. The pot or kettle is arranged within the saddle and frame and is provided at 45 its upper edge with an annular external flange 18 which rests upon the upper side of the annular saddle 13 and is secured 50 thereto by screws 40, or otherwise.

The raising of the kettle for pouring its contents into the spout is preferably effected by attaching a hoisting tackle to a pair of eyes or lugs 19 on the rear edge of 55 the kettle.

The means for agitating the contents of the pot or kettle are constructed as follows:

20 represents a bridge or cross piece extending normally across the top of the kettle and pivotally connected at its rear end 60 with the rear part of the frame so that it can swing vertically independently of the kettle and its saddle while the front end rests on the front part of the kettle and is adapted to be connected thereto by bolts 65 or screws 24, as shown in Fig. 1. The pivotal connection between the bridge and frame is preferably effected by a horizontal pin 21 passing transversely through the rear end of the bridge and two lugs 22 arranged 70 on the adjacent part of the frame. The bridge may be lifted so that the frame and agitator mounted therein is removed from the kettle by removing the bolt 24 and connecting a hoisting device with 75 an eye 23 at the front end of the bridge. On its central part the bridge is provided with a vertical bearing 26 in which is journaled the upper part of a central, upright shaft 25. The latter is 80 turned by means which preferably comprise a horizontal shaft 27 arranged above the bridge and journaled in bearings 28, 28 thereon, the inner end of this horizontal shaft being operatively connected by a pair 85 of intermeshing bevel gears 29, 30 secured respectively to the horizontal and vertical shafts 27 and 25 while the outer end of the horizontal shaft is provided with a sprocket wheel 31 which is adapted to receive a 90 sprocket driving chain belt.

Normally arranged within the kettle and secured to the lower end of the central upright shaft 25 is a main agitating or stirring blade 32 which sweeps the entire internal 95 space within the kettle and mixes the contents therein. In addition to this the material is also further mixed by a pair of supplemental agitating or stirring blades 34 which are arranged on opposite sides of the 100 central shaft 25 and turn about individual axes arranged parallel with the axis of rotation of the main mixing blade 32. The pivotal connection between each supplemental blade and the main blade is preferably 105 effected by means of a supplemental upright shaft 33 journaled on the main blade and the turning of both supplemental blades about their own axes is effected by a master or sun gear wheel 35 secured to the under- 110

side of the bridge concentric with the central shaft and meshing on its opposite sides with planetary gear-wheels 36 secured to the upper ends of the supplemental shafts 33. In this manner the supplemental blades are turned about their own axis and also are moved bodily with the main agitator blade around the axis of the latter, thereby thoroughly agitating and mixing the materials under treatment in the kettle while being heated.

For the purpose of emptying the kettle the agitating mechanism is first swung rearwardly out of the kettle independently of the same and then the kettle may be swung forwardly so that its contents are discharged into the spout 12, as shown by dotted lines in Fig. 2, this operation being performed easily and conveniently and with safety to the operators.

I claim as my invention:

1. A supporting frame provided with a spout, a saddle mounted on said frame and capable of being tilted toward said spout,

a kettle mounted on said saddle and arranged normally within said frame but movable with said saddle, and means for stirring the contents of said kettle mounted on said frame and capable of being raised independently of said kettle and saddle so as to clear the same.

2. A supporting frame provided with a spout, a saddle mounted on said frame and capable of being tilted toward said spout, a kettle mounted on said saddle and arranged normally within said frame but movable with said saddle, and means for stirring the contents of said kettle mounted on said frame and capable of being raised independently of said kettle and saddle so as to clear the same and comprising a vertically swinging bridge extending across said kettle and pivoted at one end on said frame opposite to the pivotal connection between the frame and saddle, and rotatable stirring members arranged in said kettle and mounted on said bridge.

OLIVER S. SLEEPER.
